United States Patent Office

Des. 207,566
Patented May 2, 1967

207,566

FREE STANDING FIREPLACE

Anthony J. Carsello, Los Angeles, Calif., assignor to
Space Planner Company, Inc., North Hollywood, Calif.

Filed Sept. 13, 1965, Ser. No. 86,967

Term of patent 14 years

(Cl. D81—7)

Fig. 1.

Fig. 2.

Fig. 3.

Fig. 4.

Fig. 5.Fig. 6.FIG. 1 is a front view of a free standing fireplace showing my new design;

FIG. 2 is a rear view thereof;

FIG. 3 is a top plan view of the free standing fireplace;

FIG. 4 is a bottom plan view taken from the bottom of FIG. 3;

FIG. 5 is a side view thereof, taken from the side of FIG. 3; and

FIG. 6 is a perspective view of a free standing fireplace taken from above the front end, showing my new design.

I claim:

The ornamental design for a free standing fireplace, substantially as shown.
